UNITED STATES PATENT OFFICE.

SAMUEL M. FULTON, OF POMONA, CALIFORNIA.

PUMPING-HEAD.

1,050,443.

Specification of Letters Patent. Patented Jan. 14, 1913.

Application filed February 16, 1912. Serial No. 677,956.

To all whom it may concern:

Be it known that I, SAMUEL M. FULTON, a citizen of the United States, residing at Pomona, county of Los Angeles, State of California, have invented certain new and useful Improvements in Pumping-Heads, of which the following is a specification, reference being had therein to the accompanying drawing.

10 This invention relates to certain new and useful improvements upon my former Patent, U. S., No. 997,445, granted to me July 11, 1911, the object being to obtain a uniform up motion and a quick down motion in 15 order to produce a lap in the plungers so that the column of water will be continuous as the eccentrics pass the dead center whereby a non-pulsating pump is obtained.

Another object of the invention is to provide a double acting pump head which will 20 operate with a minimum amount of friction and in which overhanging bearings are avoided and a direct central pull on all of the parts is obtained in order to dispose 25 with any rubbing or twisting.

A further object of the invention is to provide novel means for producing a slow up motion and a quick return whereby the 30 length of travel of the plungers can be readily adjusted.

A still further object of the invention is to provide a double acting pump head which is so constructed that the load is taken slowly in order to prevent any jerking 35 whereby all danger of injuring the mechanism is prevented.

Other and further objects and advantages of the invention will be hereinafter set forth and the novel features thereof 40 defined by the appended claims.

In the drawings—Figure 1 is a front elevation of my improved double acting pumping head showing the application of the same to a pump; Fig. 2 is a top plan view 45 of Fig. 1; Fig. 3 is a vertical section taken on line 3—3 of Fig. 1; Fig. 4 is a side elevation, partly in section, of one of the walking beams and eccentrics showing the manner of adjusting the antifriction roller carried by the walking beam to produce the 50 desired result; and Fig. 5 is a diagram showing the variable speed of the plungers in order to produce the lap so as to obtain a continuous column of water.

55 Like numerals of reference refer to like parts in the several figures of the drawings.

In the drawings, 1 indicates a foundation upon which is arranged a frame 2 provided with bearings 3 in which is revolubly mounted a drive shaft 4 having a pulley 5 over which is adapted to pass a driving belt, not shown, said shaft being adapted to be driven at a uniform rate of speed and the outer end thereof being mounted in a bearing 6 carried by a standard 7. The shaft 4 is provided with one or more pinions 8, but herein shown two in number, which mesh with drive gears 9 mounted upon a driven shaft 10 journaled in bearings 11 and on which are keyed eccentrics 12, 13 and 14, 60 the two outside eccentrics 12 and 14 being keyed upon the shaft opposite to the eccentric 13 for the purpose later described. 65

Extending upwardly from the frame 2 are standards 15 provided with bearings 16 in 70 which is mounted a beam shaft 17 on which are mounted the walking beams 18, 19 and 20, said beams being provided with semi-circular bearings 21 which fit over the shaft 17 and are secured in position thereon by 75 co-operating bearings 22 as shown in Fig. 3.

Each of the beams carries an antifriction roller 23 mounted in a frame 24 which is 80 adjustably mounted upon the beam and as herein shown, each frame carries bolts 25 extending through slots 26 formed in the beams in order to allow the frames to be moved longitudinally thereon, said frames being locked in their adjusted position by 85 nuts 27. While I have shown this particular manner of adjusting the antifriction rollers in respect to the eccentrics, it is, of course, understood that any other manner 90 of mounting the same may be employed without departing from the spirit of my invention. 95

The outer end of the walking beam 18 is apertured in which is mounted a pin 28 carrying links 29 pivotally connected at 30 to the arm 31 of a guide sleeve 32 which is 100 slidably mounted on a guide rod 33 arranged in suitable bearings 34—35, at its opposite ends as clearly shown in Fig. 3 in order to maintain the center pump rod 36 carried by the arm 31 in a vertical plane so that the same will pass through the stuffing box without any danger of injuring the same. The outside beams 19 and 20 are provided with bifurcated outer ends carrying pins 37 on 105 which are mounted rods which have their lower ends pivotally connected at 39 to a cross-head 40 provided with a bearing sleeve 110

41 mounted upon the guide rod 33, said cross-head being connected to the outside pump rod 42 and as herein shown, the pumping head is arranged so that the central beam 13 driving the inside piston is moved upwardly while the two outside beams 12 and 14 are moving downwardly driving the outside piston, and vice versa.

In order to hold the antifriction rollers 10 into contact with the eccentrics at all times and to draw the beams downwardly after they have been forced upwardly by the eccentrics, I provide each of the frames 24 with a flexible band 43 which surrounds the 15 corresponding eccentric and is provided with antifriction rollers 44 riding upon the face of the eccentric in order to reduce the friction as much as possible. The ends of the band 43 are pivotally connected to a 20 rocking member 45 mounted upon the shaft carrying the roller 23. While I have shown and described this band carried by the member 45 of the frame 24, it is of course understood that the same can be carried by the 25 beam by providing means for adjustably connecting the ends thereof to the beam so that the same can be shifted as the antifriction roller frame is adjusted.

From the foregoing description, it will 30 be seen that I have provided a pumping head in which friction is greatly reduced, antifriction rollers being provided for this purpose and by having the antifriction rollers adjustably mounted upon the beams 35 in advance of the driven shaft, a quick down motion is obtained and a uniform up-motion in order to obtain a lap of the plungers. If the antifriction roller was pivoted directly over the driven shaft, the upward and down- 40 ward movement would be the same and as the main object of pump heads of this character is to obtain different movements of the strokes, it will be seen that I have provided novel means for obtaining this result. By 45 arranging the roller in advance of the driven shaft, I also produce a straight upward lift of the walking beams by the eccentrics whereby a direct upward thrust is obtained and all side thrust avoided.

The operation of the invention is as follows: The driving shaft 4 being driven at a uniform rate of speed rotates the driven shaft 10 through the medium of the gears and pinions 8 and 9 on which the eccentrics 55 12, 13 and 14 are mounted and it will be seen that the eccentrics 12 and 14 are fixed opposite to the central eccentric 13 and rotate in unison so that the walking beams 18 and 20 will be simultaneously raised so as 60 to lift the outside pump piston and at the same time the inside walking beam is being drawn down by the strap, the stroke of the pistons being regulated by adjusting the antifriction rollers in respect to the driven shaft. The movement of the pistons can be

varied by adjusting the roller upon the beam and as in the diagram in Fig. 5, it requires a turn of seven-twelfths of the main shaft to raise the plungers and five-twelfths to let them down, giving a lap in the plungers 70 of one-twelfth of a revolution of the gear.

What I claim is—

1. In a pumping head, parallel walking beams, a driven shaft, eccentrics carried by said shaft, and rollers adjustably carried by 75 said beams traveling on said eccentrics.

2. In a pumping head, the combination with a driven shaft, of oppositely arranged eccentrics carried by said shaft, oscillating beams arranged above said eccentrics, rollers carried by said beams traveling upon said eccentrics, straps carried by said beams surrounding said eccentrics, and driving connections from said beams. 80

3. In a pumping head, the combination 85 with a driving shaft, of a parallel driven shaft, meshing gears carried by said shafts, eccentrics mounted upon said driven shaft, walking beams having roller bearings upon said eccentrics, and means for adjusting 90 said roller bearings longitudinally upon said beams.

4. In a pumping head, the combination with a series of oscillating walking beams, of frames adjustably mounted upon said beams, 95 antifriction rollers carried by said frames, a driven shaft carrying eccentrics upon which said antifriction rollers travel, straps carried by said frames surrounding said eccentrics, and driving connections from said 100 beams.

5. In a pumping head, the combination with a driven eccentric, of a beam oscillated by said eccentric, and an adjustable co-operating member carried by said beam and 105 contacting with said eccentric for regulating the movement thereof.

6. In a pumping head, the combination with a frame, of a drive shaft mounted in said frame, pinions carried by said drive shaft, a driven shaft, gears carried by said driven shaft meshing with said pinions, eccentrics arranged upon said driven shaft, oscillating beams arranged above said eccentrics, frames adjustably mounted upon said beams, rollers carried by said frames traveling upon said eccentrics, straps carried by said frames surrounding said eccentrics and provided with antifriction rollers, and driving connections from each of said beams. 110

7. A pumping head comprising a series 115 of oscillating beams, a driven shaft, eccentrics carried by said driven shaft for oscillating said beams, a guide rod, a guide member mounted upon said rod, links connecting said guide member to the central beam, a pump piston connected to said guide member, a cross-head carrying a guide member mounted upon said guide rod, rods connecting said cross-head to the outside beams, 120

125

130

means for adjusting the point of contact between said eccentrics and beams and a pump rod connected to said cross-head.

8. In a pumping head, the combination 5 with a frame having parallel driving and driven shafts, meshing gears carried by said shafts, standards carried by said frame, a shaft mounted in said standards, beams mounted upon said shaft, oppositely arranged 10 eccentrics carried by said driven shaft, frames adjustably mounted upon said beams, rollers carried by said frames bearing upon said eccentrics, straps surrounding said eccentrics connected to said frames, and 15 driving connections from each of said members.

9. In a pumping head, the combination 20 with a driven shaft, of oppositely arranged eccentrics carried by said driven shaft, oscillating beams arranged above said eccentrics 25 provided with longitudinal slots, frames carrying bolts extending through said slots, nuts mounted on said bolts for locking said frames in their adjusted position on said beams, rollers carried by said frames traveling upon said eccentrics, and driving connections from each of said beams.

10. In a pumping head, the combination 30 with a walking beam, of an eccentric arranged under said beam for oscillating said

beam, and means for adjusting the point of contact between said eccentric and beam for regulating the speed of travel of said beam in its up and down movement.

11. In a pumping head, the combination 35 with a pivotally mounted member, of a rotary member for oscillating said pivoted member, and means for shifting one of said members for adjusting the point of contact between said members. 40

12. In a pumping head, a walking beam, a driven shaft, an eccentric carried by said shaft for oscillating said beam, a member movably mounted upon said beam in advance of said driven shaft and coöperating 45 with said eccentric for obtaining a slow up-stroke and a fast down-stroke of said beam.

13. In a pumping head, a walking beam, a driven shaft, eccentrics carried by said shaft, a roller adjustably carried by said 50 beam traveling upon said eccentric, and a strap pivotally carried by said beam surrounding said eccentric.

In testimony whereof I affix my signature in presence of two witnesses.
